LIFTING APPARATUS

Gaston Louis Regnier, Montmorency, Seine-et-Oise, France, assignor to Richier, Paris, France, a company of France

Filed Dec. 14, 1966, Ser. No. 601,590

Claims priority, application France, Jan. 3, 1966, 46,780, Patent 1,469,647
1 Claim. (Cl. 212—71)

ABSTRACT OF THE DISCLOSURE

For lifting and positioning prefabricated floor slabs into prepared grooves in the walls of a building construction, a monorail track is supported by a beam of greater length than the building and divided into a first section of triangulated framing inside which the prime mover is located, a second section supporting the monorail from suspending rods, and a third section projecting from the building and of jib shape including the monorail as a part of the jib. A carriage and hoist traveling on the monorail is moved and powered by the prime mover.

The present invention relates to a lifting apparatus which is more particularly adapted to be used in the construction of multi-story buildings, wherein the walls are erected previous to the setting of the flooring. This is done, for instance, in the building erected by the method described in the French Patent No. 1,249,542 of Nov. 20, 1959, according to which walls are erected by means of sliding forms and continuous concreting, said walls being provided at every story level with horizontal grooves enabling thin prefabricated slabs to be slidingly fixed therein, the flooring being subsequently laid on said slabs.

In carrying said method into practice, one of the problems lies in the positioning of said thin prefabricated slabs, which positioning requires picking up the slabs outside the building being erected, lifting them to the height required and introducing them into said building.

To solve said problem, it has been suggested to use a monorail fixed under the cross girders of the sliding forms, which monorail protrudes unsupported from the building and consists of an I-shape on which a pulley block travels. Said pulley block, which is most often electrically controlled, is sent to the end of the rail, outside the building, and fetches the load lying on the ground, which load is then lifted and brought inside the construction by causing the pulley block to travel on its rail.

This arrangement, however, has a drawback in that the dead weight of the pulley block is added to the weight of the load, whereby the weights of the loads to be handled are limited. As a matter of fact, the weight of a pulley block having the lifting capacity required for ordinary loads and the span required for serving high buildings ranges from 690 to 800 kg.; since in the present state of sliding frame techniques the allowable overloads are about 1500 kg., the available useful load ranges from 600 to 700 kg. Furthermore, when the pulley block and the load are at the unsupported end of the monorail, the rocking action tending to lift the working platform is increased by the two loads adding to each other, and it is then necessary to overload uselessly said platform to counterbalance said action.

For great lifting heights, as, for instance, in tower buildings, the known electrically driven pulley blocks cannot provide the required lifting speeds and cable winding capacities, unless their weights and spaces occupied are increased substantially.

Lastly, such plants have a drawback in that they require as running rails heavy shapes which are difficult to

2

handle, can be lengthened or shortened only by means of fish plates lacking rigidity, and require a horizontal triangulation in their unsupported portions owing to the elasticity of the shapes in this direction.

5 The invention obviates the drawbacks mentioned hereinabove by providing an apparatus which allows solving advantageously the problems of lifting and positioning the prefabricated slabs in the buildings erected by the method mentioned hereinabove, while being, of course, adapted to be used in any other applications.

10 The apparatus of the invention includes a monorail track constituted by a beam the length of which is greater than that of the structure, so that one of its ends protrudes unsupported outside said structure. Said beam is used as a track for a lifting carriage of the type used in jib cranes and includes three areas, to wit: a first area where the monorail is hung on the girders of the sliding forms by means of a triangulated framing inside which the gears for moving the carriage and lifting the load are housed; a second area where said monorail is hung on the 15 above-mentioned girders merely by means of suspending rods; and a third area protruding unsupported outside the structure, wherein the monorail is carried by and is an integrant part of a jib-shaped frame.

20 25 Thus the lifting apparatus according to the invention comprises three sections differently designed, each of which is adapted to its function, namely, a section designed for the gears and grouping the winches, motors and electric equipment, the central section designed only for the suspension of the rail on the cross girders of the 30 sliding forms so as to distribute suitably the loads thereon, and the end section designed with a view to obtaining a suitable overhanging.

With respect to the known apparatus, the apparatus of 35 the invention provides the following main advantages:

Since the beam is similar to a crane jib, it is possible to use standard commercial elements, such as, for instance, travelling carriage, lifting and traversing winches, remote control devices, safety devices, that is, members and devices identical with those commonly used in jib cranes.

In service, the useful load alone bears on the end of the unsupported section.

40 45 The length of the apparatus and of the unsupported section thereof can be varied at will.

The dead weight of the lattice beam is lower than that of an I-shape having the same inertia.

50 The invention, together with its advantages and further features, will be clearly understood from the following description, with reference to the appended diagrammatic drawing which illustrates, by way of non-limiting example, an embodiment of the lifting apparatus of the invention. In said drawings:

FIGURES 1 and 2 are views of same, in side elevation and in top plan respectively;

55 FIGURES 3 and 4 are cross-sectional views of same, on lines 3—3 and 4—4 of FIGURE 1 respectively.

2 indicates the working platform resting on the girders 3 strutting the sliding forms, and 4 indicates the shape 60 which is to be used as a monorail for a traversing and lifting carriage 5 of the type used in jib cranes, said shape 4 having a length such that one of its ends protrudes unsupported outside the structure under construction.

Said monorail may be divided into three areas, A, B, C, 65 respectively.

In areas A, the monorail shape 4 is hung on the girders 3 by means of a framing made of triangulated members 6, the shape of which is arranged for housing and supporting the gears, such as lifting winch 7, gear 8 for 70 moving the carriage, etc.

In area B, the monorail 4 is connected to the girders 3 by means of triangular suspensions 9, and its length and

the number of members constituting said monorail may be varied according to the conditions under which the apparatus of the invention is to be used, namely, the size of the building under construction, the spacing of the girders.

In area C, the monorail forms the lower edge of a lattice framing 10 of triangular cross-section and having the shape of a crane jib, which gives it both rigidity and lightness. A return pulley 12 for the hoisting cable 13 is disposed at the end of said framing.

Obviously, the invention is not limited to the sole embodiment thereof described hereinabove and to the sole application thereof given hereinabove by way of example. It covers, on the contrary, all modifications thereof falling within the scope of the appended claim.

I claim:

1. A load lifting apparatus, in particular for lifting prefabricated slabs to be positioned between two walls erected by means of continuous concreting and sliding forms connected by cross girders, characterized in that said girders support a monorail track the length of which is greater than that of the structure under construction, so that one of its ends protrudes unsupported outside said

structure, said track being used for moving a lifting carriage of the type used in jib cranes and including three sections, a first section where the monorail is hung on the girders of the sliding forms by means of a triangulated framing housing the shape of which is arranged to house and support gears carried by said carriage for moving the carriage and lifting the load, a second section where said monorail is hung on the above-mentioned girders merely by means of suspending rods, and a third area protruding unsupported outside said structure, wherein said monorail is carried by and is an integral part of a jib-shaped frame.
